HAMMER MILL ROTOR STRUCTURE

Matthew E. Hamilton, Dearborn, Mich., assignor
to Harry Ferguson, Inc., Detroit, Mich., a cor-
poration of Delaware

Application February 21, 1947, Serial No. 729,925

1 Claim. (Cl. 241—191)

1 The present invention relates to hammer mills and more particularly to a mill adapted to be belt driven from a tractor power takeoff or similar high speed power source.

That hammer mills have achieved considerable success where large quantities of grain must be ground for feed is attributable to the advantages to be derived and which include constantly high operating efficiency, the production of feed having a great range of fineness, and the fact that the mill is neither injured by the presence of small foreign bodies in the feed nor dulled by running empty.

However, standing in the way of increased use of hammer mills, particularly on farms of average or small size, is the high initial cost of present day mills and the fact that difficulty is frequently experienced in belt-driving such devices at an efficient speed from a tractor power takeoff.

Furthermore, conventional mills do not include adequate provision for adjusting and centering the bearings to decrease bearing wear and shaft vibration at high rotative speeds.

Accordingly, it is an object of the present invention to provide an improved hammer mill particularly suitable for belt-driving at high speeds from a tractor power takeoff. It is a related object to provide a hammer mill in which the bearings are not only constructed and arranged so as to reduce wear and vibration at high milling speeds to a minimum, but in which bearing take-up is effected automatically and in which manual adjustment after long periods of use may be easily and quickly accomplished by the user without disassembling any part of the structure.

It is another object of the invention to provide a hammer mill in which improved means are employed for applying clamping pressure to the hammer blades, the degree of clamping pressure being subject to checking or adjustment externally and without disturbing any portion of the apparatus.

It is still another object to provide a hammer mill adapted to be belt driven from a tractor power takeoff but which includes means for enabling trouble-free operation at speeds considerably higher than the speeds normally available at the power takeoff pulley, and which is nevertheless simple and inexpensive in construction, eliminating the necessity for precise bearing alignment or other accurate machine work in its manufacture.

2 Other objects and advantages of the invention will be apparent from the following detailed description taken in connection with the accompanying drawings in which:

5 Figure 1 is a general perspective view of a hammer mill constructed in accordance with my invention and showing the manner in which a sacking attachment may be mounted thereon.

10 Fig. 2 is a fragmentary perspective view showing the opposite side of the hammer mill disclosed in Fig. 1.

15 Fig. 3 is a side elevation of the body portion of the hammer mill and showing the internal construction in dotted outline.

20 Fig. 4 is a vertical section taken along line 4—4 of Fig. 3 and revealing particularly the manner in which the bearings are mounted and adjusted.

25 While the invention is susceptible of various modifications and alternative constructions and uses, I have shown in the drawings and will herein describe in detail one embodiment of the invention. It is to be understood, however, that I do not intend to limit the invention by such disclosure, but aim to cover all modifications and alternative constructions and uses falling within the spirit and scope of the invention as expressed in the appended claim.

30 Referring now to Figs. 1 and 2, it will be seen that the hammer mill includes a housing or body portion indicated generally at 10 into which grain is fed by means of a feed chute or hopper 11. Projecting outwardly from the side of the housing 10 is a shaft 12 having a drum-shaped pulley 14 thereon which is adapted to be belt driven from the power takeoff of a tractor. The latter causes rotation of a hammer mechanism to be described. After the grinding has been completed, the grain falls to the bottom of the housing 10 from whence it is removed by means of a blower 15 (Fig. 2) being conveyed upwardly through a conduit 15 and deposited into a hopper or sacking attachment 18 which may, if desired, be mounted directly on the mill housing.

35 It has been found that the common types of feed are most efficiently milled at rotative speeds as high as 3,000-3,200 revolutions per minute or even higher. In order to step up the tractor power takeoff speed into this range, it is necessary to use a pulley 14 which is extremely small in diameter as compared to the pulley on the tractor. The use of speeds of this order of magnitude is, furthermore, accompanied by a number of problems, primarily of which are guidance

of the driving belt, increased wear and vibration, and the necessity for frequent and accurate bearing adjustment. As the discussion proceeds it will be seen that such difficulties are inherently solved in a very efficacious manner by the disclosed structure.

Turning now to Fig. 3 it will be seen that the mill housing 10 includes a lower portion 10a and an upper portion 10b hinged thereto about a horizontal hinge 19 for purposes of access, the two portions 10a, 10b being kept in normal engagement by any desired type of clamp 20 located opposite the hinge. The shaft 12 passes through the housing 10 transversely at about the separation line, being supported on the sidewalls 20, 21 in bearing assemblies 22, 24 which include supporting collars or housings 25, 26. The latter are in turn supported by brackets 28, 29 which in the present embodiment take the form of angle iron strips extending horizontally along the walls 20, 21 and fastened thereto by any suitable means, for example by riveting or welding. In order to maintain a predetermined axial distance between the bearing collars, the latter are rigidly fastened to the brackets 28, 29 by means of throughbolts 30, 31.

Internally, the bearing assemblies 22, 24 will be seen to mount bearings of the conical anti-friction type, each having an outer race 32 and having an inner race 34 snugly embracing the shaft 12. Corresponding races will be noted to be in opposition, that is, oriented with respect to one another in a manner which prevents axial displacement of the shaft 12. The bearing assemblies further include inwardly extending shielding flanges 36 for preventing the entry of dirt and other foreign matter into the bearing housing, and the assembly 22 is further shielded by an end cap 37.

Mounted on the main shaft 12 and extending radially outward therefrom are a series of hammer blades 38, each of which is provided with a hexagonal opening (not shown) to register with the hexagonal surface of a central portion 12a of the shaft 12. Each of such blades includes a hammer 40 which is preferably of the reversible type and fastened at the end of the blade by means of appropriate bolts 41 passing therethrough. This arrangement permits of the use of identical hammer assemblies which may be interchangeably mounted on the shaft in sets of three assemblies disposed 60° apart.

In accordance with one of the aspects of the invention, means are provided for securely clamping the hammer blades 38 on the shaft 12 to insure that they extend radially therefrom and are secured against vibration at high rotational speeds and under conditions of rapid feeding of grain through the mill. To this end cylindrical spacers 42 are employed which have a collar portion 44 spaced from the shaft and the axially presented edges of which are machined parallel. Such spacers 42 are centered by means of a central web or flange 45 which is formed integral with the collar 44. The latter construction not only provides a large amount of gripping surface at a point radially removed from the shaft but obviates any misalignment of the hammer blades 38 which may be due to the presence of a burr or local deformation of a blade in the region of the hexagonal aperture which is punched or otherwise formed therein.

Means are also provided for causing the assembly of hammer blades 38 and spacers 42 to be rigidly clamped together by a clamping force

which is transmitted through one of the inner bearing races and adjustably applied from outside the mill housing. To resist the clamping force, a flanged collar 48 is fastened by a pin 47 or any other suitable method to the right-hand end of the shaft 12, preferably on a cylindrical portion 12b of reduced diameter. At the other end of the hammer assembly is a somewhat similar flanged collar 49 which is telescoped over the cylindrical portion 12c of the shaft 12 and arranged in abutting engagement with the inner race 34 of the left-hand bearing. In order to permit a limited amount of clamping movement of the collar 49, it is internally relieved by an annular groove 50 which is of sufficient radial extent as to clear the hexagonal lands on the portion 12a of the shaft. To apply clamping force to the left-hand edge of the inner race 34, a threaded nut 51 is used which is screwed on the end of the shaft 12. In the present embodiment the force exerted by the nut 51 is transmitted through the adjacent pulley 14 and a sleeve 52 of small outside diameter, the latter being telescoped over the shaft 12 and abutting the inner bearing race 34. Slippage of the pulley 14 is prevented by a key 53, and a similar key may be used in connection with sleeve 52 if found necessary.

With such structure in mind it will be apparent that advancement of the nut 51 will cause the inner race of the bearing 34 to be moved to the right (as viewed in Fig. 4), which will cause the collar 49 to be likewise urged to the right, thereby applying clamping pressure serially to the hammer blades 38 and the separating spacer members 42. It is, therefore, a simple matter not only to cause original tightening of the assembled elements, but also to check from time to time that the assembly is still in a tightened condition merely by applying a wrench to the accessibly located nut 51. It may incidentally be noted that a single nut 51 not only causes clamping of the internal assembly but in addition provides a means whereby the pulley 14 may be readily removed, if desired, and replaced by one of different diameter.

It has been found in the case of hammer mills driven at high speeds that a considerable proportion of the bearing wear and shaft vibration which is encountered is attributable to the fact that the bearings are not accurately aligned and to the lack of means for adjusting the bearings from time to time to take up play and to establish a predetermined degree of preloading. In accordance with one of the main features of the invention, therefore, means are provided for constantly insuring proper alignment in spite of inaccurate initial assembly and for further providing for takeup of the bearings both automatically and by means of a single threaded adjustment outside of the mill housing. In accomplishing the latter and to obtain additional smoothness of operation, resilient cushioning is employed between the outer races and the associated bearing housings.

As shown in the preferred embodiment illustrated in Fig. 4, such resilient cushioning may be accomplished by an annular rubber insert 54, which is interposed between the outer bearing race 32 and an inserted cup member 55 and which is preferably vulcanized to both of them. The insert 54 allows a limited amount of relative twisting movement to take place between the outer bearing race and the housing which surrounds it when the shaft 12 is secured in place. It will be apparent, then, that it is merely necessary to align

the bearing housings 25, 26 approximately during fabrication of the mill, any residual discrepancy or misalignment being compensated for or absorbed by deformation of the rubber cushion. By choosing rubber of the proper physical characteristics, considerable angular deflection may occur without causing any appreciable unbalance of the forces on one side of the bearing as compared to the forces on the side diametrically opposite. The latter construction has reduced the 10 exacting and time consuming alinement of the bearing housings to a quantity production operation in which simple jigs and fixtures may be used and without particular attention being paid to the matter of exact initial alinement. It is also 15 to be noted that the use of the rubber cushions causes the bearings to remain in alinement during the entire life of the machine and regardless of the mistreatment to which it may be subjected.

The specific means here used for taking up 20 wear on the bearings and for preloading them is shown at the right-hand portion of Fig. 4, where it will be observed that the inner race 34 of the bearing assembly 22 is snugly telescoped over the end portion 12b of the shaft and may be axially moved through a path of adjustment indicated by the gap 56. Abutting the right-hand edge of the inner bearing race is a nut 58 which is in threaded engagement with the end of the shaft 12 and which may be locked thereto in a desired 25 position of adjustment by means of a cotter key 59. To take up play in the bearing, it is merely necessary to advance the nut 58 along the shaft which results in leftward movement of the inner race 34. The latter shortens the distance between 30 the two inner races and tends to increase the pressure exerted by the inner races against the corresponding outer race. The fact that movement of the adjusting nut 58 is effective simultaneously and equally to change the axial load 35 on both of the bearings will be more clearly seen when it is considered that engagement of the thread tends to draw the shaft 12 to the right with respect to the bearing housing 26 and the wall 21 to which it is rigidly secured.

In hammer mills not including conical bearings backed by a resilient cushion such as the rubber ring 54 here illustrated, the side play in the bearings increases the vibration of the shaft 12 and greatly accelerates bearing wear. It is necessary in the usual case, therefore, to take up on the bearing frequently, exercising care not to cause excessive preloading which in itself may shorten bearing life. In the present structure, however, it is sufficient to put the rubber cushions under a slight amount of initial preloading, and any subsequent bearing wear is automatically taken up by the expansion of the rubber. It is thus sufficient to take up play in the bearings by adjustment of the nut 58 at long intervals, such 40 adjustment being accomplished very readily by a non-skilled user of the mill without danger that the bearings will be excessively preloaded. The torque which must be applied to the nut 58 to turn it may serve as a measure of the preloading force existing in both of the bearings.

Turning now to the lower portion of Figs. 3 and 4, it will be seen that a screen 60 is used for limiting the size of the particles discharged from the mill, the latter screen being semi-cylindrical 45 in shape and coaxial with the main shaft. Arranged below the screen and centrally in the mill housing is an auxiliary shaft 61 which is journaled in suitable bearings 62, 64. Arranged along the body of the shaft 61 and rotatable therewith is

a screw conveyor 65 which conveys the milled grain into the intake of the blower 15. The latter includes an impeller 66 which creates an air blast elevating the milled grain through the conduit 16 and into the hopper or sacking attachment 18. The bearing 62 is preferably supported in outboard relation to the housing by a casing 62a bolted to the housing. The casing has an open top, as at 62b, providing an air inlet to the lower portion of the housing immediately below the screen.

This high opening not only prevents the escape of ground material from the mill but causes air drawn into the housing by the blower to travel crosswise of material falling from the screen and thus tend to carry it toward the blower.

Power for rotating both the conveyor 65 and the impeller 66 is derived from a sheave 68 which is mounted at the left-hand end of shaft 61 (as viewed in Fig. 4). The latter is coplanar with a driving sheave 69 which is inboard of the driving pulley 14 and fixed to the sleeve 52 by welding or the like. Both of the sheaves 68, 69 are grooved to receive a high speed V-belt 70 which is trained over them.

Considerable difficulty has been experienced in the case of prior art hammer mills in operating at a high rotative speed on the order of 3,000-3,200 R. P. M., because of the tendency of the 30 driving belt leading from the tractor power take-off to walk off of the drive pulley in one direction or the other. The latter difficulty is particularly troublesome with a driven pulley of extremely small diameter used to obtain a high step-up speed ratio. In one of its aspects, therefore, my invention contemplates the use of a radially extending flange which is of an outer diameter considerably greater than that of the pulley 14 and which is generally radially aligned with the inboard end thereof. In the illustrated embodiment such flange is indicated at 71 and is formed integral with the sheave 69. Because of the fact that the flange is of an outer diameter which greatly exceeds that of the drive pulley, the flange will 35 engage both runs of the belt at a substantial distance from the pulley and provide an effective belt guide. In order to prevent the belt from slipping off the outboard end of the pulley 14, the entire hammer mill may be oriented at a 40 slight angle so that any creeping tendency on the part of the belt is inward and against the flange 71.

I claim:

In a hammer mill the combination comprising a housing, a rotatable shaft extending horizontally in the housing and having a fixed collar spaced inwardly from one end thereof, a hammer assembly including a series of longitudinally stacked hammer blades mounted for clamping adjacent one another on the central portion of said shaft, first and second conical thrust bearings arranged at the opposite walls of said housing for supporting said shaft, each of said bearings having an outer race mounted on the respective walls of the housing and facing outwardly with respect thereto, each of said bearings having an inwardly facing inner race for cooperating with the respective outer races, the inner race of said first bearing being telescoped on the shaft and having a shiftable collar adjacent its inner edge arranged to abut said series of hammer blades for clamping the blades against said fixed collar, a nut at the end of the shaft associated with said first bearing for drawing up the inner race thereof tightly against said stacked hammer blades to rigidify

the blade assembly, the inner race of said second bearing being slidably telescoped on said shaft and having a lockable nut for not only retaining the race but for drawing up the race to reduce the spacing between the two inner races and consequently effect simultaneous and equalized adjustment of the play in said bearings, the inner race of said second bearing having sufficient clearance relative to said fixed collar so as to permit maximum takeup for wear of the bearings normally required during the life thereof.

MATTHEW E. HAMILTON.
